RAZOR BLADE FOR SAFETY RAZOR
DEVICES

Adolph Baudis, New York, N. Y.

Application February 25, 1935, Serial No. 8,133

4 Claims. (Cl. 30—94)

The subject of the present invention are certain new and useful improvements in razor blades for so-called safety razor devices.

From the point of view of economy the different 5 razor blades which are commonly used in the different safety razor apparatus mean a considerable waste of the very valuable quality-steel, which is a rather expensive material; besides that most types of razor blades, in particular the 10 so-called double-edged blades are very liable to be broken by stresses in handling them, because their middle zone is considerably weakened by the different holes or slots stamped into them as means for securing the right positioning of the 15 blade and for the purpose of identifying the different types of blades made by different manufacturers.

The first object of the present invention is to curtail the waste of valuable material and to provide 20 a new and improved razor blade, which offers the greatest economy for the manufacturer as well as for the user. Another object of the invention is to produce an improved razor blade which has not less than four cutting edges, but 25 which blade in spite of its greater number of cutting edges retains the universally accepted size of the standard razor blade, so that this new and improved razor blade will fit into all and any apparatus of the different types of symmetrically 30 built safety razors, which are in common use. The new and improved type of razor blades, which I devised in order to carry out the before said objects of the invention, and which blade hereininafter will be called the combination-blade, consists 35 of two narrow double-edged lamina-blades, arranged side by side at some distance from each other, and held together by connecting links, which are jointed to the lamella blades, so that the combination-blade has two outer operative 40 cutting edges and two inner unoperative edges. The construction and the connection of the different parts in my new combination blade is such as to allow the one lamina-blade together with the connecting links to be swung in the plane of the 45 combination blade round the joints in the other lamina-blade, so as to bring the originally inoperative inner cutting edges into operative position at the outside of the combination blade.

In order to make the invention perfectly clear 50 and well understood I shall describe now in detail some preferred embodiments of the before-said inventive idea, taking reference to the drawing, in which the

Figures 1 to 3 illustrate a first embodiment, 55 which comprises two lamina blades, and two con-

necting links, pivoted to the blades, the Figures 1 and 2 showing the two alternative settings or adjustment of the different parts for use in a razor apparatus, and Figure 3 showing an intermediary position in changing from the setting 5 Figure 1 to the setting Figure 2.

Figure 4 shows a variation of the first embodiment, in which a single connecting lashing is pivotally jointed to the two lamina blades.

Figure 5 illustrates a second embodiment of the 10 invention, in which two lamina blades are connected by two lashes, which are hooked into holes of the lamina blades.

Figures 6 to 8 illustrate a third embodiment, in which two lamina-shaped blades are held together by two wire-made connecting links, hooked into holes of the lamina blades, the Figs. 6 and 7 showing the two alternative settings of the parts for use of the combination blade, and Figure 8 showing an intermediary position in changing 20 from the one setting to the other setting.

Figures 9, 10 and 11 show, in an enlarged scale, cross-sections through the connections between the blades and the connecting links in the Figs. 1 25 to 3, 4, and 5 to 8 respectively.

Referring now in particular to the drawing in the combination blade of the first embodiment according to the Figs. 1 to 3 two narrow lamina-shaped blades 21, 21', are provided each at both their longer sides with sharpened cutting edges 30 22, 22'. Two connecting lashes 23, 23' are fastened to the two blades at points 24, 24' in the longitudinal axial zones of the blades near to their ends. The joints or pivotal connections are preferably made in the most simple manner as 35 shown in detail in the Figure 9: a hole 25 is stamped through the connecting link 23 (23') and through the blade 21 (21'), and the material of the one member is pressed through the hole, turned up over the other member and chased to 40 the outside, so as to form a small brim 26 around the upper end of the hole 25. The one end of the lashes extends crosswise on top of the one blade, whereas the other end of the lashes extends crosswise below the other blade. In consequence of this arrangement the one blade, (for instance blade 21) together with the connecting links may be swung in the plane of the combination-blade around the joints or pivotal connections 45 (24') in the other blade (21'), and such change 50 of the mutual positions of the lamina blades from the Figure 1 through the Figure 3 to the Figure 2 brings the originally inner and inoperative cutting edges 22' to the outside of the combination 55 blade into the operative positions. If the con-

necting lashes are pivoted close to the ends of the blades, so that the lashes extend somewhat beyond the ends of the blades, as it is shown in the illustrated example, then the combination blade 5 can be easily handled by two fingers pressed from the outside against the lashes, avoiding thus the danger of the fingers being cut by the sharp edges of the blades, and furthermore the cutting edges need not be touched at all, so as to remain absolutely clean and sterilized.

10 The two connecting lashes 23, 23' have in their middle broadened parts at both sides recesses 27, the outer portions of which are rounded or wedge-like broadened, but have preferably a rectangular bottom; such shape of the recesses 27, as shown in the drawing, facilitates the first introduction and the definitive correct setting of the combination blade into the razor apparatus by the means of the central longitudinal rib or the two short 15 blade-positioning pins which are provided in most of the safety razor apparatus of the different types. Some kind of razor apparatus however have no such central rib or pins, but they have four blade-holding hooks or shoulders at the 20 four corners of the blade supporting member. In order to be fitted for use likewise in these last-mentioned apparatus, the combination blade according to the present invention may be clipped further at the four corners of each lamina-blade, as it is shown by short-dotted lines in the Figures 25 1 to 3, and by full lines in the Figures 4 to 8. These rectangularly clipped recesses 28 fit into or below the said hooks or shoulders at the corners 30 of the blade supporting members of the last mentioned apparatus.

In the new and improved combination blade according to the Figure 4 two narrow lamina-shaped blades 29, 29' with cutting edges 30, 30' on their longer sides and blade positioning recesses 28 at their corners are united by means of one single connecting lash 31, which is fixed at the middle points 32, 32' of the two blades. The connection of jointing between the lash 31 and the lamina blades may be made either 45 by means of rivet-bolts 33, as shown in the Figure 10, or in the manner described above with reference to the Figure 9. The connecting lash is broadened in its middle part, and it has a central hole 34, adapted to give free passage to the central bolt, which is usually provided in the safety razor apparatus, for the purpose of pressing together the blade-clamping cap and the blade carrying member of the apparatus.

50 In the combination blade according to the Figure 5 the two lamina-shaped blades 35, 35', having lateral cutting edges 36, 36' and corner recesses 28, are provided, near to the ends of their longitudinal axial zones, with holes 37, such as it may be seen best at the lower end of the left side 55 of Figure 5. The connecting links between the blades are lashes 38, 38', which are provided, in their broadened middle parts, with blade-positioning recesses 27, such as they have been described above with reference to the Figures 1 to 3. At the ends of the connecting lashes 38, 38' however are tongues 39, such as shown in the upper end of the right side of Figure 5, which tongues, in assembling the combination blade, are passed through the holes 37 of the blades, and 60 are bent over the other sides of the blades, so as to form hooks 49, on which the blades are hooked. In the same manner, as it has been described above with reference to the previous examples, so likewise in the construction according to the Figure 5 the connecting lashes over-

lap the one blade at its upper side, whilst overlapping the other blade at its lower side, and as the oppositely bent hooks 49 can turn within the holes 37, in this construction likewise the one blade together with the connecting links may be 5 swung round the pivotal holes in the other blade, so as to bring the inner cutting edges 36' into operative positions at the outside of the combination blade.

10 In the last embodiment of the invention, as shown in the Figures 6 to 8, the combination blade consists of two laminae 41, 41', provided with lateral cutting edges 42, 42' and with corner-recesses 28, and further with holes 43 in the longitudinal axial zones of the blades near to their 15 ends, which blades are united by wire-made and end-hooked connecting links 44, 44', the hooks at the connecting links being bent in opposite directions and being hooked from opposite sides into the holes 43 of the blades. The hook-connection between one blade and one connecting link, which is shown in the Figure 11, in an enlarged scale, may be considered as a cross-section of the corresponding parts either in Figure 5, or in the Figures 6 to 8. It is evident however 20 and considered as falling within the scope of protection of the present invention, that the ends of the tongues 39 at the lashes in Figure 5 or the ends of the connecting wires 44 in the Figures 6 to 8, instead of forming hooks, may be pressed 25 to the form of headed rivets, similar to those shown in the Figure 10.

I claim:

1. A combination-blade, comprising in combination: two double-edged lamina blades arranged 35 side by side at some distance from each other and having holes in their longitudinal axial zones; and blade-holding means, overlapping with their ends partly the two blades at different sides; and oppositely directed hooks at the extremities of the connecting means, hooked from different sides into the holes of the blades, so as to allow the one blade together with the connecting means to be swung, in the plane of the combination-blade round the connection in the 40 other blade; and blade-positioning recesses at the four corners of each lamina-blade.

2. A combination-blade, comprising in combination: two double-edged lamina blades arranged side by side at some distance from each other; 50 blade-holding links, overlapping with their ends partly the two blades at different sides near to the ends of the blades, and having recesses at both sides of the middle part of the links, for positioning the combination-blade; and pivot-like 55 joints between the ends of the links and the blades in the longitudinal axial zones of the blades and of the links, so as to allow the one blade together with the links to be swung in the plane 60 of the combination-blade round the pivot-joints in the other blade.

3. A combination-blade, comprising in combination: two narrow lamina-shaped double-edged blades arranged side by side at some distance from each other; and a pair of blade-holding 65 links near to the lateral end-zones of the combination-blade, said links overlapping partly the two lamina-blades on the upper side and on the lower side respectively of their opposing edges; and joint-forming connections between the links 70 and the lamina-blades, adapted to allow both lamina-blades to be swung at the same time in the plane of the combination-blade round their joint-forming connections with both links.

4. A combination-blade, comprising in combi- 75

5 nation: two double-edged lamina-blades arranged side by side at some distance from each other and having holes in their longitudinal axial zones; and blade-holding means, overlapping with its ends partly the two blades at different sides; and oppositely directed hooks at the extremities of the connecting means, hooked from different sides

into the holes of the blades, so as to allow the one blade together with the connecting means to be swung in the plane of the combination-blade round the connection in the other blade, in such manner, that the end of the swung blade remains in the plane of the combination-blade. 5

ADOLPH BAUDIS.
